(57) **CLAIM**

The ornamental design for a camera column, as shown and described.

DESCRIPTION

FIG. 1 is a perspective front and side of a camera column according to my new design;

FIG. 2 is an enlarged exploded perspective view of the top portion of the camera column, the lower portion and support structure are omitted for ease of illustration;

FIG. 3 is a perspective front and side of the camera column being fully extended, the mounting bracket is omitted for ease of illustration; and,

FIG. 4 is an enlarged perspective view of the mounting bracket on a fragmentary lower portion of the camera column, the upper portion and support structure are omitted for ease of illustration.
